DESIGN FOR A CONTAINER FOR PERFUME BOTTLE OR SIMILAR ARTICLE

John H. Willmarth, Chicago, Ill., assignor to Lucien Lelong, Inc., Chicago, Ill., a corporation of Illinois

Application March 15, 1941, Serial No. 99,632

Term of patent 3½ years

To all whom it may concern:

Be it known that I, John H. Willmarth, a citizen of the United States and a resident of the city of Chicago, in the county of Cook and State of Illinois, have invented a new, original, and ornamental Design for a Container for Perfume Bottle or Similar Article, of which the following is a specification, reference being had to the accompanying drawing, forming a part thereof.

On the drawing:

I claim:

The ornamental design for a container for perfume bottle or similar article, as shown.

JOHN H. WILLMARTH.
